UNITED STATES PATENT OFFICE.

OSCAR SEARS BRANHAM, OF ROSWELL, NEW MEXICO.

WEATHER-STRIP.

1,343,304.

Specification of Letters Patent. Patented June 15, 1920.

Application filed October 23, 1918. Serial No. 259,387.

To all whom it may concern:

Be it known that I, OSCAR SEARS BRANHAM, a citizen of the United States, and a resident of Roswell, in the county of Chaves and State of New Mexico, have invented 5 certain new and useful Improvements in Weather-Strips, of which the following is a specification.

My invention is an improvement in weather strips, and has for its object to provide a strip of the character specified, mounted to move laterally and longitudinally of a door, and controlled by the opening and closing of the door for movement in such lateral and 15 longitudinal directions, to tightly seal the space between the bottom of the door and the sill when the door is closed.

In the drawings:

Figure 1 is a front view of the lower portion of a door looking from the outside, with 20 the door partly open;

Fig. 2 is a similar view, with the door tightly closed;

Figs. 3 and 4 are sections on the lines 3—3 25 and 4—4, respectively, of Fig. 2, each view looking in the direction of the arrows adjacent to the line;

Fig. 5 is a perspective view of the weather strip with the parts detached, showing a 30 modified form of spring.

The present embodiment of the invention is shown in connection with a door 1 of usual construction, said door being mounted in the usual frame or casement 2 which has 35 the usual sill 3 at the bottom of the door, and it will be noticed that the bottom of the door is spaced above the sill slightly to provide for a free opening and closing movement of the door.

40 The improved weather strip comprises a plate 4 having its upper edge flanged, as indicated at 5, for a purpose to be described, the flange overlying the adjacent face of the body of the strip in spaced relation, as 45 shown more particularly in Figs. 3, 4 and 5, and this strip is secured to the outer face of the door by means of screws 6 which are passed through vertical slots 7 in the strip and into engagement with the material of 50 the door.

A second strip 8 carries at its lower edge a flexible strip 9 of rubber or the like, the said strip 9 having one edge received within a 55 groove 10 extending longitudinally of the strip 8 on the inner face thereof, the said

groove being formed by folding back the edge of the strip on the body in close relation, and then bending the extremity of the edge in spaced relation in the opposite direction. The upper edge of this strip 9 is 60 bent laterally, as indicated at 11, to lie at an obtuse angle with respect to the body, and at approximately the same angle as the flange 5 of the strip 4, and this bent portion 11 moves beneath the flange 5. 65

The strip 8 has arc shaped slots 12 near its ends which are engaged by threaded stems 13 extending laterally from the strip 4. Leaf springs 15 are arranged between the stems and the strip 8, the said springs being 70 secured to the strip 8 at the top of the groove 10 at one end and bearing at the other against the threaded stem 13, as shown in Figs. 2 and 4, and these springs act normally to move the strip 8 upwardly and toward 75 the hinged side of the door. In Fig. 5 the springs 15 are replaced by coil springs 14, which are connected at one end to the top of the groove 10 and have eyes at the other for engaging the stems 13. 80

The strip 9 is slidable with respect to the strip 4 a distance corresponding to the length of the slots 12, and these slots, being cam shaped or eccentric, tend to move the strip downwardly when it is moved in one 85 direction longitudinally and upwardly when it is moved in the opposite direction. By means of the screws 6 engaging the slots 7 the position of the strip 4 may be varied with respect to the door. 90

In operation, with the door open, the parts of the improved weather strip occupy the position shown in Fig. 1, with that end of the strip 8 adjacent to the hinge of the door extending beyond the adjacent end of the 95 portion of the strip 4 and into position to be engaged by a cam plate 16 mounted on the inner face of the adjacent side member of the casement. This engagement between the end of the strip 8 and the cam plate will 100 move the strip 8 longitudinally of the strip 4, and because of the engagement of the stems 13 with the slots 12 the strip 8 will be moved downwardly as well as laterally of the door, into position of Fig. 4, where the 105 bottom edge of the flexible strip 9 will engage the sill. So long as the door remains closed, the parts will occupy the position of Figs. 2 and 4 and the space beneath the door will be tightly sealed. As soon, however, as 110

the door is partially opened, the weather strip may spring into the position of Figs. 1 and 3, where it will clear the floor.

I claim:

- 5 A weather strip comprising a strip of metal adapted to be secured transversely of the lower end of a door, and having vertical slots for receiving a securing means, said strip having its upper edge turned backwardly upon itself to form an inclined flange, a second strip mounted to slide longitudinally of the first strip, said second strip having arcuate slots near its ends, and having its upper edge inclined for engagement beneath said flange in conforming relation thereto and the first strip having stems engaging the arcuate slots to constrain the second strip to move laterally when it is moved

longitudinally of the first strip, disks disposed against the outer face of the second 20 named strip and covering the arcuate slots therein and held in place by nuts threaded on said stems, springs arranged between the strips and acting normally to move the second strip in a direction away from the bottom of the door, said second strip having one 25 end normally extending beyond the adjacent end of the other strip and adapted to engage the door casing to move said second strip downwardly when the door is closed for the 30 purpose specified.

OSCAR SEARS BRANHAM.
